UNITED STATES PATENT OFFICE.

JAVIER LUIS BUSTOS, OF SANTIAGO DE CHILE, CHILE.

TIDE-MOTOR.

1,105,249.

Specification of Letters Patent. Patented July 28, 1914.

Application filed June 27, 1913. Serial No. 776,149.

To all whom it may concern:

Be it known that I, JAVIER LUIS BUSTOS, a citizen of the Republic of Chile, residing in Santiago de Chile, in said Republic, have 5 invented certain new and useful Improvements in Tide-Motors, of which the following is a specification.

This invention relates to an improved tide-motor, which is operated by the variations 10 of the level of the sea—variations which are produced by the tides along the shore and natural inlets, and in all places where the waves do not merely wash the shore, but roll up at considerable differences in their level. 15 These fluctuations of level are taken advantage of by means of constructions that have the property of taking up and utilizing the power of the waves, which constitutes the basis of my invention.

20 After careful observations at different points of the coast, I have been able to note that the normal fluctuations of the sea when calm, vary from eighty centimeters to two and a half meters, while when the sea is 25 rough, they may reach fifteen meters. The interval of time in which these differences of level may take place is sometimes delayed up to eight seconds, but in most cases one may count on an average of four seconds between the rising and falling movements.

In the accompanying drawings, Figure 1 is a side-elevation of my improved tide-motor, Fig. 2, a detail vertical section through the shiftable cross-bar on line 2, 2, Fig. 1, and 35 Fig. 3, a horizontal section on line 3, 3, Fig. 1.

Similar reference characters denote corresponding parts in the figures of the drawings.

40 My apparatus is operated by means of the alternating fluctuations in the level of the sea and is composed of the following mechanisms, a float 1 whose size or capacity is in proportion to the force which is to be developed and which is guided by means of rollers *r* at diametrically opposite points along vertical posts 6 and 7 that are anchored into the bottom of the sea. The top of the float 1 is connected by a piston-rod 20 45 with a piston 21 of an air-compressing pump 2. In order to prevent damage to the pump by the quick rising of the sea-level or any interference with the working of the apparatus, an automatic system is used by means 50 of which the action of the pump is regulated, and which consists of the following

instrumentalities: a fixed cross-bar 15 which encircles and guides the upper end of the pump-cylinder 2 and a lower cross-bar 14 which is attached to the pump-cylinder and which is locked by two spring-bolts 8 in its ends into notches of the posts 6 and 7. To the top of the float 1 are attached two upright posts 9 having forked upper ends, and which engage fulcrumed lever 16, which have the object that, in case of a rapid rising of the level of the water, the float, after having made a complete stroke of the piston, rises and lifts the pump-cylinder, after first withdrawing the spring-bolts from the notches of the posts 6 and 7, preventing thereby injury and damage to the parts. The spring-bolts 8 lock the cross-bar 14 of the pump-cylinder into one of the higher pairs of notches of the posts. On the descending of the float 1 the cross-bar of the pump-cylinder is released by the withdrawing of the spring-bolts 8, which is accomplished by a chain 13 connecting the float with a fulcrumed lever 11, the forked rear portion of which is connected by chains 10 with the lower ends of the fulcrumed levers 16. The lever 11 is fulcrumed to a bracket-arm 12 on the cross-bar 14, as shown in Fig. 2. The release of the spring-bolts produces the lowering of the pump with the float until it is returned into its lowermost position with the falling wave, producing thereby the lowering of the piston ready for the next compressing action of the same in the pump-cylinder. It is readily understood that at low tide the float, by its own weight, will lower itself also, so as to lower the piston in the pump and suck in the air into the pump-cylinder. As through a suction-valve 17 at the upper end of the pump-cylinder 2 air is admitted when the piston descends, when the float rises with the level of the water, the air is compressed in the pump-cylinder and conducted through a flexible tube 3 having a check-valve 18 from the upper end of the pump-cylinder to a receiver 4, the size of which is proportioned with the size of the tide-motor. The compressed air is stored in the receiver and supplied by means of a tube 5 at any desired pressure to the motor, by which the compressed air in the receiver is utilized.

From the foregoing it is seen that the tide-motor consists mainly of a pump 110 for compressing air, which pump is operated by the float and raised and lowered

with the same. The compressed air is stored in the receiver for motive purposes, the receiver acting in the nature of a reservoir for the storage of power, in the same manner 5 as a boiler acts for a steam-motor. The tide-motor is of comparatively simple and effective construction and can be used in many instances along the coast-line of the oceans, being operated automatically by the 10 tides. By transforming the energy stored up in the receiver into electric energy, the power can be transmitted to great distances.

I claim:

1. A tide-motor, comprising upright posts 15 anchored to the bottom of the sea, a float guided thereon, an air-compressing pump supported on said upright posts, means for locking the pump to said posts, means for releasing the pump from said posts by the 20 upward motion of the float, and means for returning the pump by the downward motion of the float.
2. A tide-motor, comprising fixed upright 25 guide-posts, a float guided thereon, an air-pump supported slidingly on said upright posts, means for locking the pump to said posts, means for releasing the pump from said posts by the upward motion of the float, means for returning the pump with 30 the downward motion of the float, a receiver for the air compressed by the pump, and a flexible valved tube between the pump and receiver.
3. A tide-motor, comprising upright posts 35 anchored to the bottom of the sea and provided with notches, a float guided thereon, an air-compressing pump guided in a cross-bar, a cross-bar attached to the lower por-

tion of the pump, a cross-bar attached to the posts for guiding the upper portion of 40 the pump, spring-bolts in the ends of the lower cross-bar, means between the float and the spring-bolts of the lower cross-bar for releasing them and lifting the pump with the float, a lever-mechanism connected with 45 the spring-bolts, and a chain between said lever-mechanism and the float for releasing the spring-bolts and returning the pump with the float into lowermost position.

4. A tide-motor, comprising a pair of 50 notched posts anchored into the bottom of the sea, a float guided on said posts, an air-compressing pump above the float, a cross-bar for guiding the upper end of the pump, a cross-bar attached to the lower end of the 55 pump, spring-bolts in the ends of the lower cross-bar adapted to engage the notches of the posts, fulcrumed levers connected with the spring-bolts, forked rods on the float for engaging the levers, withdrawing the spring-bolts and raising the pump, a lever-mechanism supported on the lower cross-bar, chains connecting said lever-mechanism with the fulcrumed levers, and a chain connecting the lever-mechanism with the float 60 for releasing the spring-bolts and returning the pump with the float into lowermost position.

In testimony, that I claim the foregoing as my invention, I have signed my name in 70 presence of two subscribing witnesses.

JAVIER LUIS BUSTOS.
